WHEELED TOY

Application filed April 27, 1931. Serial No. 533,158.

My invention relates to improvements in wheeled toys which are particularly adapted for use by small children. The object of the invention is to provide a toy which will give healthy exercise to a child and enable him to simulate a movement such as that of riding a galloping horse and to utilize the movement and effort to propel the toy.

The invention consists essentially of a toy having a rear wheel driven through a crank and a train of parts terminating in a seat upon which the rider sits, in which means are provided for permitting a movement of variable length to be transmitted into a crank throw of definite length, as will be more fully described in the following specification and shown in the accompanying drawing, in which:—

Fig. 1 is a plan view of the toy.

Fig. 2 is a longitudinal view showing its mechanical arrangement.

Fig. 3 is a diagrammatic view showing the normal stroke movement of the seat in solid line and the possible movement of said seat in dotted line.

Fig. 4 is a sectional view showing a modification.

In the drawing like characters of reference indicate corresponding parts in each figure.

The numeral 1 indicates a pair of side panels which are held in spaced relation by transverse members 2 and 3. A foot board 4 is secured to the lower edges of the panels 1 and extends laterally beyond to accommodate the feet of the user, and a cover board 5 is mounted upon the upper edges of the panels to cover the space therebetween. A bracket 6 extends forwardly of the transverse member 2 which is apertured adjacent its forward extremity to receive a king bolt 7.

The numeral 8 indicates generally a steering column (shown with a portion cut away in Figure 2 to illustrate its mounting) which column consists of a pair of spaced strips 9 having transverse strips 10 through which the bolt 7 extends to form a fulcrum for the steering column. The lower extremities of the strips 9 constitute a fork 11 in which a steering wheel 12 is rotatably mounted, and at the upper end of the strips a handle 13 is

transversely mounted for the purpose of imparting movement to the steering column and the wheel 12 to steer the toy.

A pair of bearings 14 are secured to the under edges of the side panels 1 in which a shaft 15 is freely journalled, this shaft is provided with a crank 16 between the bearings 14 and is fitted at opposite ends with wheels 17, one of which is secured to the shaft to turn therewith and the other is freely mounted thereon in the manner usually employed in pedal driven toy construction. A pair of brackets 18 are mounted upon the upper edge of each of the side panels 1, which are connected together by a hinge pin 19. The curved leaf spring support 20 is provided intermediate its length with a U-shaped bracket 21 which is fulcrumed upon the hinge pin 19. At the upper extremity of the leaf spring support 20 a seat 22 is secured and at its lower extremity an eye 23 is formed, which connects through a rod 24 with the crank 16. A compensating spring 25 is secured at one end to the lower extremity of the support 20 and is anchored at its other end to the transverse member 3, which spring is adapted to exert an upward lift to the seat approximating the weight of the user.

In the modification shown in Figure 4 the seat support indicated by the numeral 26 is substantially rigid and is but slightly deflected in use, but a tension spring 27 is interposed between its lower extremity and the forward end of the rod 24.

This toy is intended primarily to be driven by a small child when seated upon the seat 22 with his feet on the footboard and gripping the handle 13, the movement of the body being similar to that made when riding a galloping horse.

It will be readily seen that a child making such movement will not restrict his body to a certain definite stroke and maintain that same length of stroke at all speeds and during the varying degrees of excitement to which he will be subjected in the course of his play. It is therefore conceivable that while the length of stroke of the seat 22 as prescribed by the stroke of the crank will be as X (see Figure 3) the stroke imparted to said seat

by the user may be as Y (see Figure 3) since the seat is resiliently connected through the several parts to operate the crank. If on the other hand the seat had a definite stroke proportionate to that of the crank and the child failed to make properly synchronized movement therewith the crank would fail to carry over and the toy would cease to travel. The leaf spring support 20 in the device as shown in Figures 1, 2 and 3 and the spring 27 as shown in Figure 4 serve to compensate between the variable movement of the body upon the seat and the definite stroke of the crank, so that a substantially even speed of rotation may be imparted thereto.

15 What I claim as my invention is:

In a toy having road wheels, a foot rest and a seat, a crank operatively connected to one of the wheels, a leaf spring pivotally mounted intermediate its length to the toy, said spring supporting the seat adjacent one end and being operatively connected adjacent the other end to the crank.

Dated at Vancouver, B. C., this 18th day of April, 1931.

HERMAN EDWARD CLARKE.
